BEACH TOWEL

Bernice G. Karney, 212 E. Broadway,
New York, N.Y. 10002

Filed Mar. 13, 1972, Ser. No. 234,472

Term of patent 14 years

Int. Cl. D6—13
U.S. Cl. D6—265

The single figure is a top plan view of a beach towel showing my new design.

I claim:

The ornamental design for a beach towel, as shown.
